Lacey, Lacey,

ATTORNEY.

UNITED STATES PATENT OFFICE

FRANK BAUMAN, OF HONESDALE, PENNSYLVANIA, ASSIGNOR TO WAYNE MANUFACTURING COMPANY, OF HONESDALE, PENNSYLVANIA

FLYER TWISTING FRAME

Application filed August 15, 1928. Serial No. 299,837.

This invention relates to spinning and chiefly to the twisting mechanism of the type embodying a flyer twister frame, the purpose being to provide for the ready removal and replacement of the flyer, yet preventing casual displacement of the flyer from the spindle should it become loose.

The invention contemplates a novel form of flyer including a hub, or block formed with an annular groove, and a two armed flyer having its middle portion fitted in the annular groove of the hub and retained therein by means of two oppositely disposed pins.

While the drawing illustrates a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawing hereto attached, in which:—

Figure 1 is a longitudinal, central, sectional view of a bobbin and flyer twister embodying the invention showing the same mounted upon a spindle.

Figure 2 is an enlarged fragmentary, sectional view at a right angle to Figure 1 of the flyer and adjacent end of the bobbin.

Figure 3 is a detail sectional view on the line 3—3 of Figure 2 looking in the direction of the arrows.

Figure 4 is a detail sectional view on the line 4—4 of Figure 2 looking in the direction indicated by the arrows.

Corresponding and like parts are referred to in the following description and designated in the several views of the drawings by like reference characters.

The numeral 1 denotes a spindle of a flyer twisting frame and 2 designates the body of the bobbin which is adapted to slip upon the spindle 1 and engage the same frictionally so as to rotate therewith. A recess 3 is formed in the upper end of the bobbin 2 and receives the reduced portion 4 of a cap or head 5. Screws 6 or analogous fastenings secure

the cap to the body of the bobbin 2. The cap or head 5 is formed with a central opening in which is fitted a collar 7. A flange 8 projects inwardly from the outer end of the collar 7. The collar 7 is pressed into the opening 3 and retained therein by frictional engagement.

The twister comprises a hub or block 10 formed intermediate its ends with an outer enlargement 11 and at its inner end with an eccentric flange 12 of a diameter to pass snugly through the opening defined by the inner flange 9 of the collar 7.

The outer enlargement 11 is formed with an annular groove 13 in which is fitted a curved portion 14 of the flyer. The hub or block 10 is formed with an opening to receive the spindle 1.

The flyer includes two arms 15 which constitute end portions of a wire, the middle portion of which is bent into semi-circular form, as indicated at 14, to snugly fit within the annular groove 13 and about the hub of the twister. Pins 16 extend across the annular groove 13 and their ends are supported in the parts bordering upon the groove. The pins 16 are disposed in the angle formed between the arms and the semi-circular portion 14 of the flyer. The arrangement admits of ready replacement of a broken or crippled flyer as will be readily comprehended.

As shown most clearly in Figure 2 of the drawing the flyer is centered with reference to the bobbin by means of the spindle 1, hence the eccentric flange 12 is retained in position to underlap the inwardly disposed flange 9 at the outer end of the collar 7. This prevents displacement of the flyer from the spindle. The hub 10 and flyer 15 are known to the trade as brass flyer block.

Having thus described the invention, I claim:

1. In a flyer twisting frame, the combination with a bobbin having the spindle retaining opening enlarged at its outer end, a flange projecting inward from the bobbin across the enlarged portion of the spindle receiving opening, a flyer, and a flange projecting outwardly from the flyer and overlapping the flange of the bobbin to prevent outward displacement of the flyer, the parts being nor-

mally held in operative position by means of the spindle.

5 2. In a flyer twisting frame, the combination with the bobbin, and flyer, of a flange projecting inwardly from the bobbin, and a companion flange projecting outwardly from the flyer, the two flanges being held in given position by means of the spindle.

10 3. In a flyer twisting frame, the combination with the bobbin, a cap secured to the outer end of the bobbin and having a central opening, a collar secured within the opening of the cap and formed with an inwardly disposed flange, and a flyer formed with an eccentric flange adapted to enter the said collar and overlap the flange thereof, the parts being held in operative position by means of the spindle.

15 4. In a flyer twisting frame, the combination of a bobbin, a cap at the outer end thereof provided with a central opening, a collar within the opening of the cap and having an inner flange at its outer end, and a flyer having an eccentric flange at its inner end normally disposed within the said collar and overlapping the inner flange thereof to prevent accidental displacement of the flyer which normally is held in given position by means of the spindle.

20 5. In a flyer twisting frame, a bobbin, an annular flange thereon, a flyer, and an eccentric flange on the flyer to coact with the flange of the bobbin and retained in cooperative position by the spindle when the bobbin and flyer are mounted thereon to prevent accidental displacement of the flyer.

In testimony whereof I affix my signature.
FRANK BAUMAN. [L.S.]
